SHOE

Harold Zisla, South Bend, Ind., assignor to Mishawaka
Rubber and Woolen Manufacturing Company, Mishawaka, Ind., a corporation of Indiana

Application June 24, 1955, Serial No. 36,683

Term of patent 7 years

(Cl. D7—7)

Fig. 1.

Fig. 2.

Fig. 1 is a side view of a shoe showing my new design; and

Fig. 2 is a top view of the shoe of Fig. 1.

The dominant feature of my design is the surface ornamentation of the upper fabric of the shoe.

I claim:

The ornamental design for a shoe, as shown and described.
